Primary Examiner—Alan P. Douglas*Assistant Examiner*—Caron D. Veynar*Attorney, Agent, or Firm*—Wenderoth, Lind & Ponack[57] **CLAIM**

The ornamental design for an automatic cut sheet feeder for a computer printer, as shown and described.

DESCRIPTION

FIG. 1 is a right side, top and front perspective view of an automatic cut sheet feeder for a computer printer showing my new design;

FIG. 2 is a front elevational view thereof;

FIG. 3 is a rear elevational view thereof;

FIG. 4 is a top plan view thereof;

FIG. 5 is a bottom view thereof;

FIG. 6 is a left side elevational view thereof;

FIG. 7 is a right side elevational view thereof;

FIG. 8 is a sectional view thereof, taken along line VIII—VIII in FIG. 2, with interior construction omitted; and,

FIG. 9 is a right side, top and front perspective view showing the article of the claimed design mounted on a computer printer. The broken lines showing of the computer printer are for illustrative purposes only and form no part of the claimed design.
